CONTROL MEANS FOR SWITCH MACHINES

Application filed August 4, 1927. Serial No. 210,561.

This invention relates to control apparatus, and more particularly to means for controlling a power operated switch machine on a railway system from a distant tower or office.

In controlling railway traffic controlling apparatus, and this is especially true of a power operated switch machine, it is highly important that the apparatus should be such as not to be operable accidentally. In providing means for controlling a switch machine there are three important requisites to be taken into consideration, namely, (1st) a switch machine should not be started unless it is safe to operate the same at the time, (2nd) if the operation of such switch machine is once initiated such operation should be permitted to continue until the machine has completed its operating stroke irrespective of traffic conditions ahead; and, (3rd) the device for controlling the same, which of necessity must have stick or maintaining operating characteristics, should be of such construction that after once operated to a certain position it cannot be accidentally displaced from such position.

In view of the foregoing and other important considerations, it is proposed in accordance with the present invention to provide electrically controlled circuit controlling mechanism which is mechanically constructed to have a tendency to remain in its last operated position, and which is electrically constructed so that if slightly displaced from such last operated position it will be electrically returned to such position. A further object of the present invention resides in the provision of energy saving means which automatically cuts off the electric current when the circuit controlling mechanism has assumed the operated position.

Other objects purposes and characteristic features of the invention are in part pointed out in the specification hereinafter, and are in part apparent from the accompanying drawings.

In describing the invention in detail reference will be made to the accompanying single figure of the drawings in which an em-

bodiment of the invention has been illustrated in the form of a control means and associated circuits for controlling a distant motor operated switch machine.

Structure.—Referring to the drawings, a railway track having rails 3 and 4 has been shown, from which diverges a siding having rails 5 and 6, including a track switch 1S. The position of the railway track and siding shown is a part of a railway train dispatching system, such as disclosed in the prior application of S. N. Wright, Ser. No. 120,423, filed July 3, 1926, and in which sufficient signals are provided at the end of each passing siding for controlling the entrance and departure of traffic into and out of the main track and siding of such passing siding, respectively. It is to be understood, however, that the invention may be applied to any switch machine controlled from a distant point. In the particular arrangement shown these signals have been conventionally illustrated as comprising semaphore signals, of which the signals 2 and 2D are starting signals, the signal 1 is the main track entering signal and the signal 1D is a take-siding signal. The portion of the track adjacent these signals is electrically segregated from the rest of the track by insulating joints 7, to form the usual detector track circuit, which includes the detector track relay DR conventionally illustrated by a dotted line and which includes the track battery B. The signals 1, 1D, 2 and 2D are in practice controlled by the control relay Z, and in accordance with traffic conditions ahead, in any suitable manner, for instance, as described in detail in the application above referred to.

This control relay Z is controlled through the medium of the line wire 10 from a distant train dispatcher's office or tower DT in any suitable manner. In the particular arrangement shown the control relay Z is a direct current polar-neutral relay which may be energized positively from the battery 11 when the lever L is moved in a clock-wise direction and may be energized into the reversed position when the lever L is moved in a counterclock-wise direction from its normal position.

The track switch 1S is preferably con-

trolled by a motor operated switch machine SM, including a motor preferably of the direct current series type having an armature A and a field winding F, although a direct or alternating current motor of any suitable construction may be used. This switch machine SM is of a construction so that if one of its control wires either the normal or the reverse wire is energized the motor will operate the switch points to that position, and when such operation is completed it will again open this operating circuit. This switch machine SM is preferably controlled by a circuit controller CO of the mechanical stick type, in which the movable parts tend to remain in the position to which they have been last operated. This controller CO includes oppositely disposed electromagnets having coils 15 and 16, disposed on yokes 17 and 18, respectively. These 20 electromagnets are adapted to act on an armature (not specifically shown) which in turn operates the contacts 20 and 21 toward the energized electromagnet or solenoid. It is believed that the novel features of the invention are best understood by considering the operations of the switch machine from the normal extreme position to the reverse position and back to its normal position.

Operation.—Let us first assume that the 30 train dispatcher wishes to clear a certain signal, and in order to do so moves the lever L in a clock-wise direction so as to connect the lever contact to the positive side of the battery 11. This will cause the control relay Z to 35 pick up its neutral contact 24, the polar contact 22 remaining in the right hand position, in which it is illustrated. By so energizing the control relay Z one or the other of the main track signal 1 or 2 are permitted to assume the clear position through suitable control circuits and mechanism, which for convenience have been omitted from the drawings. The lifting of the neutral contact 24 will complete the following circuit, in which 40 no current will flow because the coils 15 are shunted out since both ends of this circuit are connected to the same pole of a source of energy, such as a battery:—beginning at the terminal B+, of such source, polar contact 22, wire 23, neutral contact 24 of the control relay Z, wire 25, front contact 26 of the detector track relay DR, wire 27, contact 28 of the approach locking relay LR, wire 29, contacts 30—20—31, wire 33, coils 15, back to the same 45 terminal B.

The completion of the circuit just traced will have no material effect since there is no source of current therein. The energization of the relay Z will, however, in practice permit clearing of a signal as more clearly described in the prior application, above mentioned, from which it appears that the operator can clear signals consistent with the position the switch machine is assuming, without 50 operating such switch machine.

Let us now assume that the operator or dispatcher wishes to operate the switch machine SM to the reverse position, so as to permit a train to enter or leave the siding including track rails 5 and 6. The operator will move the lever L in the counterclock-wise direction, thereby connecting the lever contact to the negative terminal of the battery 11, which in turn will cause the control relay Z to be energized to the reverse dotted position. With the relay Z energized to the reverse position 70 the following circuit for operating the controller CO is completed:—beginning at the terminal B-, polar contact 22 of the control relay Z in the left hand dotted position, wire 23, neutral contact 24 of the same relay, wire 25, contact 26, wire 27, contact 28, wire 29, contacts 30—20—31, wire 33, coils 15, to the terminal B+ of the same battery. It is noted that this circuit is the same as the one 75 previously traced except it includes the battery. With this circuit completed the electromagnet 15—17 will operate the contacts 20—21 to their dotted position, which operation will open the circuit just traced and complete another circuit which does not include any 80 source of current, and therefore need not be considered at this time. Operation of the controller CO to the dotted position completes the following energizing circuit for the 85 motor of the switch machine SM:—beginning at the terminal B of a suitable battery, the wires 36 and 37, contacts 38—21 of the controller CO, reverse wire R, contacts 40—41 of the switch machine SM, wires 42 and 43, 90 armature A, wire 44, contacts 45—46, wire 47, field winding F, to the common return wire C connected to the other terminal of 95 said battery. The completion of this circuit will cause the switch machine SM to operate 100 the track switch 1S to the take-siding position, and after this operating cycle has been completed the circuit just traced is opened at the contacts 40—41 and 45—46. It is thus 105 seen that the energy is cut off of the controller CO when its operating stroke is completed, and in the same way electrical energy 110 is cut off of the switch machine SM when it has completed its stroke. Let us now see how 115 an electric circuit is completed when the contacts 20—21 are accidentally moved slightly away from their dotted position to which they 120 were just operated. If this occurs, the following circuit is completed, which operates 125 the contacts 20—21 to the same extreme dotted position:—beginning at the terminal B+ coils 15 of the electro-magnet 15—17, wire 33, contacts 31—20—32, wire 50, coils 16 of the electro-magnet 16—18, to the other terminal 130 B— of such battery. Although the completion of this circuit energized both of the two opposing electro-magnets, the contacts will be attracted to the last operated position, because they are nearer that electro-magnet.

and its tractive force predominates. It will be noted that the circuit just traced is again opened as soon as the armature and contacts 20-21 have been operated to the extreme position. In this connection it will further be noted that the circuit last traced is always available for returning the contacts 20-21 to the extreme position to which they were last operated, even though the control circuit including relay contacts 24, 26 and 28 is open; or in other words, this circuit, conveniently called a retaining circuit, is always available for maintaining the operating contacts of the controller CO in the last operated position. Also, if the contact 20 is accidentally moved to a position to contact with both stationary contacts 31 and 32 when the contacts 24 of relay Z as well as contacts 26 and 28 are closed, the controller CO is operated to the correct position, because the coil for operating it to the other position is shunted out by the partial circuit including contacts 24, 26, and 28.

If the operator now wishes to return the switch machine SM back to the normal straight-track position, he will operate his control lever L in a clock-wise direction to connect the line wire 10 to the positive side of battery 11, and will thereby energize the control relay Z to the normal position and complete the circuit for the control relay Z first traced, except that it will include the battery and the coils 16 instead of the coils 15, and the completion of this circuit will return the contacts 20-21 to the position in which they have been illustrated. With the controller CO returned to the normal position and with the switch machine SM in the reverse position the following circuit for operating the switch machine to the normal position is completed:—beginning at the terminal B, wires 36 and 52, contacts 53-21, normal wire N, contacts 41-54, wires 55 and 44, armature A of the switch machine motor, wire 43 contacts 56-46, wire 57, field winding F, to the common return wire C connected to the other side of said battery.

It will be noted that the current flow in the armature A of the switch machine in the normal circuit, just traced, is in the reverse direction from that of the current flow in this armature in the reverse circuit, heretofore traced; so that the motor is operated in the reverse direction and thereby operates the switch points in the opposite direction back to the normal straight-track position. In view of the operation just considered it readily appears that the controller CO is of a construction which if caused to operate to a certain position will remain in such position even though its operating circuit is opened at one of the relay contacts 24, 26 or 28 controlling the same, so that the approach of a train will not prevent operation of the switch machine after such operation has once been initiated.

This is extremely important, because it is

considered better to complete the operating stroke of the switch points after once started than to leave the points in an intermediate position, in the event there is an approaching train coming within the zone which controls the lock relay LR. This zone in practice extends braking distance from the switch points, or at least extends over a distance so that as a train enters such zone there will be sufficient time for the switch machine to complete its cycle even though such cycle has just been initiated. In this connection it is desired to point out that the lock relay LR is preferably controlled in the same way as is the relay CR in the above mentioned prior application, that is, the lock relay LR can only be energized when there is no train approaching the track switch 1S within a limited distance, or in the event there is a train approaching this must have accepted a caution signal and is preparing to stop before it reaches the track switch in question before conditions are proper for the lock relay LR to pick up. It should also be noted, that if the contacts 20-21 of the controller CO are accidentally shifted from their extreme position due to any cause, such as vibration due to a passing train, these contacts will be returned to such extreme position as soon as the contact 20 is shifted far enough to engage the contacts 31 and 32.

Having thus shown only one embodiment of the present invention and having shown a rather specific circuit arrangement connecting the various devices shown conventionally, it is desired to be understood that this has been done for the purpose of disclosing the nature of the invention and the manner in which it may be applied to a specific problem, and that this showing has not been made to illustrate the scope of the invention or the exact construction preferably employed in practicing the same; and it is further desired to be understood that various changes, modifications and additions may be made to adapt the invention to the particular problems encountered in practicing the same, all without departing from the scope of the invention of the idea of means underlying the same except as demanded by the scope of the following claims.

What I claim is:—

1. In combination, a railway track having a track switch associated therewith, a power operated switch machine for operating said track switch, a controller controlled by an operating circuit and for controlling the flow of current to said switch machine to operate the same, said controller including devices for cutting the operating current off of such controller when said controller has been operated to the last controlled position and for reapplying current to return such controller to such position if it has due to some other cause been moved from such position.

2. In combination, a railway track having a

track switch associated therewith, a power operated switch machine for operating said track switch, a controller for controlling said switch machine, a control circuit for said controller which if closed will cause said controller to assume a certain operated position, and means for again operating said controller to said certain position if it has been moved from such position due to foreign causes, said last mentioned means functioning even though said control circuit has been opened in the mean time.

3. In combination, a railway track having a track switch associated therewith, a power operated switch machine for operating said track switch, a controller for controlling said switch machine including two oppositely disposed electro-magnets adapted when alternately energized to move control contacts in opposite direction in two extreme positions, and means for closing a circuit which energizes both of said solenoids when said contacts due to foreign causes are moved from their last operated position, whereby said contacts are moved to the nearest extreme position.

4. In combination, a switch machine of the motor operated type, a circuit for said switch machine which if closed operates said switch machine from one extreme position to the other, a controller for controlling said circuit and switch machine, a circuit for said controller which if closed operates said controller to close said switch machine circuit and then open said last mentioned controller circuit, and means for closing said last mentioned circuit.

5. In combination, a switch machine of the motor operated type, a normal and a reverse circuit for said switch machine, a controller for closing one or the other of said normal or reverse circuits at one point, circuit controlling means for opening the closed circuit when the switch machine has been operated to the controlled position, a normal and a reverse circuit for the controller, switch means for closing one or the other of the normal and reverse circuits of said controller, and means for opening the last closed circuit of said controller when the controller has been operated to the last controlled position.

6. In combination, a switch machine of the motor operated type, a normal and a reverse circuit for said switch machine, a controller for closing one or the other of said normal or reverse circuits at one point, circuit controlling means for opening the closed circuit when the switch machine has been operated to the controlled position, a normal and a reverse circuit for said controller, switch means for closing one or the other of the normal and reverse circuits of said controller, and means for opening the last closed circuit of said controller when the controller has been operated to the last controlled position, said last mentioned means being of such

construction that accidental displacement of the contacts of said controller will complete a circuit to return it to the last operated position even though both the normal and the reverse circuit of said controller are open.

7. A controller comprising, two oppositely disposed electro-magnets adapted to magnetically act to move an armature in opposite directions if alternately energized, contacts and circuit wires for connecting the coils of said electro-magnet in series in a circuit with a source of current when said armature assumes any except either extreme position, and means for shunting the coils of either of said electromagnets out of said circuit.

8. A controller comprising, two oppositely disposed electro-magnets adapted to magnetically act to move an armature in opposite directions if alternately energized, stationary contacts, a movable contact for connecting the coils of said electro-magnets in series through said stationary contacts, and means including a wire connected to a stationary contact for shunting the coils of either of said electro-magnets.

9. Means for controlling a distant switch machine comprising, a controller having oppositely disposed coils for operating contacts in opposite directions when alternately energized, a circuit for connecting said coils in series with a source of electric current, a polar relay located near said switch machine which if in one energized position shunts one of said coils and when in the other energized position shunts the other of said coils, and a control circuit connecting a local tower and said polar relay for controlling the said polar relay.

10. Means for controlling a distant switch comprising, a switch machine having a normal and a reverse position, a controller for completing said normal or said reverse circuit, means for opening the completed circuit of said switch machine when it has completed its operating stroke, a normal and a reverse circuit for said controller, means for closing the normal or the reverse circuit of said controller, and means for opening the completed circuit of said controller when said controller has been operated to the position to which the completed circuit tends to operate it.

11. A circuit controller for operating switch machines comprising, two electro-magnets for operating circuit controlling means in opposite directions upon alternate energization of said electro-magnets, circuit selecting means for connecting one or the other of said electro-magnets to a line wire, and means for controlling the energization of the connected electro-magnet through the medium of said line wire.

12. A circuit controller for operating switch machines comprising, two electro-magnets for operating circuit controlling means in opposite directions upon alternate

energization of said electro-magnets, a source of current having one terminal connected to one of said electro-magnets and having the other terminal connected to the other of said electro-magnets, a line wire, circuit selecting means operated by said electro-magnets for connecting the free terminal of the electro-magnet which is capable of operating said circuit controlling means from the then operated extreme position to said line wire, and means for connecting said line wire to either of the terminals of said source of current, whereby said circuit controller is operated in response to the application of potential of one or the other polarity to said line wire and the current flow is discontinued when the circuit controller has been operated in response to the application of such potential.

20 In testimony whereof I affix my signature.
